UNITED STATES PATENT OFFICE.

ROBERT A. FORESMAN, OF ESSINGTON, PENNSYLVANIA, ASSIGNOR TO WESTINGHOUSE ELECTRIC AND MANUFACTURING COMPANY, A CORPORATION OF PENNSYLVANIA.

RAM-ACTUATING MECHANISM FOR MECHANICAL STOKERS.

Application filed June 9, 1920. Serial No. 387,614.

To all whom it may concern:

Be it known that I, ROBERT A. FORESMAN, a citizen of the United States, and a resident of Essington, in the county of Delaware 5 and State of Pennsylvania, have invented a new and useful Improvement in Ram-Actuating Mechanism for Mechanical Stokers, of which the following is a specification.

This invention relates to stokers, and particularly to mechanism for driving and controlling the movement of reciprocating rams employed in apparatus of the character designated and it has for an object to provide a simple and durable driving connection between the fuel feeding rams and the auxiliary or secondary rams which operate in the fuel retorts of the grate section.

Another object of my invention is to provide a driving connection for the purpose specified which may be adjusted so that the stroke of the auxiliary rams may be varied with relation to the stroke of the main fuel feeding ram while the stoker mechanism is in operation.

These and other objects are attained by means of a mechanism embodying the features herein described and illustrated in the drawing accompanying and forming a part hereof, wherein:

Fig. 1 is a view, partially in longitudinal vertical section and partially diagrammatic of the fuel hopper and passage of a stoker, showing the improved mechanism for connecting the auxiliary ram operating bar with the main feed ram.

Fig. 2 is a perspective view of the ram operating mechanism showing certain portions of the fuel hopper cut away.

Fig. 3 is a detailed view on an enlarged scale of the pawl and ratchet and of the selector mechanism.

Fig. 4 is a view in vertical section taken through the lug 33 of the selector 26.

Fig. 5 is a view in section showing the auxiliary rams of a multiple retort furnace in different phases of reciprocation.

Referring to the drawings, the stoker upon which the improved apparatus is shown as applied includes the usual fuel hopper 5 and ram 6 which is reciprocated beneath the fuel discharge opening 7 for the purpose of forcing fuel into a longitudinally extending retort 8. It will be understood that the stoker may be provided with any desired

number of retorts, each having fuel feeding and agitating mechanism such as that illustrated in Fig. 1, and that the fuel is forced upward out of the retorts upon rows of tuyères 9 disposed longitudinally between the retorts and forming a combustion surface or grate. The fuel upon the lower portion of the grate is agitated by means of auxiliary rams 10 which slide forward and rearward upon the bottom wall 11 of each of the retorts and which are reciprocated by means of operating bars 12. Each operating bar is connected to the associated plunger 6 by mechanism to be hereinafter described and which embodies the novel construction which I hereinafter claim. The plunger 6 is reciprocated by suitable power means, indicated at 13, which is connected thereto by means of a connecting rod 14, pivoted at one end to the plunger 6 by means of a pin 15 and at the other end to a crank shaft 16 driven by the power means.

The stoker construction above described, with the exception of the apparatus connecting the auxiliary ram with the feed ram is of the underfeed type which is well known in the art and my improvement resides in the apparatus connecting the main feed rams with the auxiliary rams whereby the stroke of the auxiliary rams may be readily varied with respect to that of the main rams or plungers, by a simple adjustment of certain parts of the apparatus. The connecting apparatus referred to includes a rocking lever 17 which is pivoted at its lower end to a bracket 18 secured to the under side of the hopper 5, and at its upper end to a pin 15 carried by the plunger 6.

The free end of the operating rod 12 is supported in a bracket 19 and is provided with a longitudinally extending slot 20 having its lower wall provided with a rack consisting of a series of downwardly directed notches 21 between which rack or ratchet teeth 22 are formed. The bar 12 is connected to the rocking lever 17 by means of a pair of links 23 which are disposed on either side of the bar and lever and are connected at one end by means of a pin or pawl member 24 which extends through the slot 20. The other ends of the links 23 are pivoted at 25 to the rocking lever 17.

It will be seen from the foregoing that when the ram 6 is reciprocated, oscillatory

movement is imparted to the rocking lever which, in turn, causes reciprocating motion of the links 23 which will hereinafter be considered as a pawl member adapted to 5 ratchet over the inclined teeth 22 when moved forwardly and to engage the teeth 22 and thereby move the rod 12 rearwardly when the pawl member is moved rearwardly by the rearward movement of the ram.

10 The slot 20 is of such length that no motion is imparted to the rod 12 by the movement of the pawl member through its entire cycle when the said member is held out of engagement with the front faces of 15 the teeth 22 of the rack, and when the bar is in its extreme forward position, as shown in full lines in Fig. 1. However, when the pawl 24 is in the forward notch 21, the bar will be moved substantially the entire travel 20 of the pawl member, the bar being moved rearwardly by reason of the engagement of the pawl with the front face of the forward tooth 22 and being moved forward by reason of the engagement of the pawl with the forward end of the slot 20. When the pawl 24 is shifted to the central notch 21, the degree of movement of the bar 12 will be reduced 25 because the distance which the pawl is capable of pushing the bar rearward is reduced 30 by the distance between the forward notch and the central notch. Upon the return stroke of the pawl it will ratchet out of the central notch and will not move the bar until the pawl engages the forward end of 35 the slot 20. When the pawl is shifted into the rear-most notch 21, the motion of the bar is still further reduced and, as previously stated, when the pawl 24 is held entirely out of engagement with the teeth 22, no motion whatever will be imparted to 40 the bar 12.

In order to control the movement of the pawl 24, a selector 26 is slidably mounted upon the bar 12 so that it is free to be moved 45 longitudinally with respect to the bar. As shown, the lower edge of the bar 12 is provided with lateral flanges 27 over which the selector is fitted in such manner that lateral displacement of the selector is prevented. 50 The rear end of the selector is provided with a face 28 which is inclined with respect to the axis of the bar at the same angle as the rear faces of the teeth 22. The selector is adapted to be moved along the bar 12 so as to 55 cover the notches 21 and thereby prevent the pawl from entering any notches thus covered. When the selector is moved rearward so as to cover the forward notch, the pawl will fall into the middle notch upon 60 its rearward stroke and move the bar substantially two-thirds of its maximum travel. Upon its return stroke, the pawl will slip out of the central notch and move over the upper face of the selector until it engages the 65 forward end of the slot 20, when it will re-

turn the bar to its original position. If the selector is now advanced until it covers both the forward and central notches, the pawl, upon its rearward stroke, slides over the selector and falls into the rearmost notch 21. 70 No motion will be imparted to the bar, however, until the pawl engages the rearmost tooth 22 when the bar will be substantially one-third of its maximum travel. The selector is of sufficient length to cover all of 75 the notches and thus prevent the pawl from engaging any of the teeth 22. When the selector is in this position the pawl will simply move backward and forward in the slot 20 without imparting any motion to the bar 12. 80 Thus the lost motion between the bar and the pawl may be varied by the adjustment of the selector with respect to the bar.

The selector is adjusted by means of a 85 lever 29 which is pivoted to a rocker shaft 30 mounted for oscillation in the upper portion of the bracket 18. A pair of levers 31 straddle the selector and are secured to the rocker shaft 30 so that they are oscillated by the movement of the lever 29. The lower ends of the lever 31 are pivotally connected to a rod 32 which is slidably connected to a depending lug 33 carried upon the selector. The rod 32 is provided at its rearward end by a limit stop 34, and the selector is yieldingly held in engagement with the stop by 90 means of a compression spring 35 disposed between the forward end of the rod 32 and the lug 33. The selector is yieldingly connected to the lever 31 so as to permit a plurality of selectors to be advanced into any desired position, regardless of the positions of the various pins 24. It will be understood 95 that the rocking shaft 30 may extend entirely across the width of the furnace and operate a plurality of selectors disposed beneath a like number of retorts. 100

It is the usual practice to drive the plungers of a battery of retorts from a common 110 crank shaft wherein the crank bearings are spaced in determined relative angular relation. The plungers actuated by the crank shaft will, therefore, operate at all times in different positions of their cycle. As 115 a result of this arrangement, certain auxiliary operating bars 12 will be in different positions with respect to each other at all times, some moving forward while others are moving rearward. In dot and dash lines I have illustrated in Fig. 1, the relative 120 position of the pin 15, rocking lever 17, link 23 and the position of the pawl 24 in the notch 21 of the bar 12, when in extreme rearward position. It will be seen 125 that if the selectors were unyieldingly connected to the levers 31, they could not be moved rearwardly because they could not pass the pawls 24, some of which would be moving rearwardly while others were moving forwardly. Because of the yielding con- 130

- nection between the selectors and their respective operating levers 31, the main lever 29 may be advanced to any desired position by causing the compression of such springs 5 as are attached to the selectors brought into contact with their respective pawls. When the pawl engaging, a selector again moves rearward, the selector will follow it by reason of the spring action until the pawl 10 starts its return stroke, and, as soon as the pawl ratchets out of the notch in which it was operating, the selector will move into the desired determined relative position with respect to the operating bar 12.
- 15 A sector 36 is provided having suitably disposed notches 37 into which the lever 29 may be moved in order to retain the lever in any desired position. It will be seen that the length of the stroke of the 20 auxiliary rams may be readily adjusted, while the stoker is in operation.
- While I have described and illustrated but one embodiment of my invention, it will be apparent to those skilled in the art that 25 various changes, modifications, additions and omissions may be made in the apparatus described and illustrated without departing from the spirit and scope of my invention, as set forth by the appended claims.
- 30 I claim as my invention:
1. Stoker mechanism comprising a ram-operating member, means for reciprocating the ram-operating member, a rack and pawl connection between the said member and the said means, and an adjustable selector associated with said connection and means adjustable at any phase of reciprocation for setting said selector, whereby the tooth of the rack with which the pawl shall engage to transmit motion to the said member may be predetermined.
  2. Stoker mechanism comprising a ram-operating member, means for reciprocating the ram-operating member, said member being provided with a rack, a pawl carried by the said means adapted to cooperate with the teeth of the rack for transmitting motion of the said means to the said member in one direction of movement of the said means, and means movable to prevent operative engagement of said pawl with one or more of the teeth of said rack.
  3. Stoker mechanism comprising a ram-operating member, means for reciprocating the ram-operating member, a rack and pawl connection between the said member and the said means, and means for preselecting in one direction of movement of said pawl the tooth of the rack with which the pawl shall engage.
  4. Stoker mechanism comprising a ram-operating member, means for reciprocating the ram-operating member, a rack carried by the said means adapted normally to engage a tooth of the rack when moved in one direction and to ratchet over the teeth of the rack when moved in the opposite direction, and adjustable selector means adapted to be moved into various relative positions with respect to the pawl for permitting engagement of the pawl with a preselected tooth of the rack.
5. Stoker mechanism comprising a ram-operating member, means for reciprocating the ram-operating member, a rack carried by the said member, a pawl carried by the said means adapted normally to engage a tooth of the rack when moved in one direction and to ratchet over the teeth of the rack when moved in the opposite direction, adjustable selector means adapted to be moved into various relative positions with respect to the pawl for permitting engagement of the pawl with a preselected tooth of the rack.
6. The combination with a plurality of reciprocable stoker ram operating members adapted to be moved relatively into different operative positions, means for reciprocating each of the said members, and a ratchet and pawl connection between each of the said members and its reciprocating means whereby reciprocating movement of the said means is imparted to the said member, of a separate selector for each said member adapted to be moved into various relative positions with respect to the pawl whereby engagement of the pawl with certain teeth of the ratchet is prevented and means yieldingly connected with the several selectors for advancing them into operative position.
7. Stoker mechanism comprising a ram-operating member provided with a toothed rack having a guideway into which the spaces between the teeth open, means for reciprocating the said member, a pawl pivotally connected to the said means and adapted to move in said guideway and operatively to engage the teeth of the rack when moved in one direction for imparting movement to the said member and to ratchet over the teeth of the said rack when moved in the opposite direction and operatively to engage an end of the guideway for imparting movement to the member in said opposite direction, a selector for preventing the pawl from engaging certain of the teeth of the rack whereby the movement imparted to the said member by the pawl may be varied, and means for moving the selector into various operative positions with respect to the pawl.
8. In a stoker, in combination, a plurality of retorts each having a ram and ram-operating mechanism for imparting a to-and-fro movement of changeable length to each associated ram, continuously operating means for actuating adjacent ram-operating members

in different phases in their to-and-fro cycle, a connecting mechanism between each said member and its actuating means comprising adjustable means for rendering the actuating means ineffective to reciprocate the said member or to give to the said member reciprocations of any stroke length of several different stroke lengths, and means for operat-

ing the said adjustable means of all of said connecting mechanisms by a single operation 10 irrespective of the position of any ram at the time of such operation.

In testimony whereof, I have hereunto subscribed my name this 28th day of May, 1920.

R. A. FORESMAN.
